Dr. A. F. Haynes,
by G. W. H. Ward, M.A.

UNITED STATES PATENT OFFICE.

DAVID F. HAYNES, OF BALTIMORE, MARYLAND.

DESIGN FOR A EWER OR JUG.

SPECIFICATION forming part of Design No. 19,576, dated January 14, 1890.

Application filed November 2, 1889. Serial No. 329,090. Term of patent 3½ years.

To all whom it may concern:

Be it known that I, DAVID F. HAYNES, a citizen of the United States, residing at Baltimore, in the State of Maryland, have invented 5 and produced a new and original Design for a Ewer or Jug, of which the following is a specification, reference being had to the accompanying drawings, forming a part thereof.

Figure 1 is an exterior side elevation of the 10 ewer, and Fig. 2 a top view of the same.

I describe the ewer as follows: The base A, as seen from its under side, is circular, and it tapers from the bottom to where it connects with the body B; but the actual point of contact is concealed by a rounded bead *a*. The 15 body B is spherical, with two central and diametrically-opposed circular panels C, which are spherical and bounded by a bead *b* and a foliated border *c* in relief. By reference to 20 the top view of the ewer it will be seen that the radius of the spherical panels is greater than that of the body proper. The center of the body is denoted by *d*, and the points from 25 which the spherical panels are struck are represented by *e*. By this union of spherical shapes with different radii the ewer has a flattened appearance when viewed from the points E and F, and when seen from the top has an elliptical form. The neck G, when seen 30 from the top of the ewer, is circular in form both at the top and bottom, and when viewed from the side presents curved lines which extend from the junction with the body to the upper edge, which is provided with a bead *f*

on the outside. The ewer has two spouts arranged diametrically opposite to each other, and they are of a uniform semi-elliptical form, as seen from the top of the ewer, with a waved outline by reason of their outside being fluted. These flutes *g* diminish in width 40 as they approach the body B, as shown. Beneath the bead *f* at the edge of the neck G is a guilloche band in relief, which stops at the first flutes of each spout. The ewer is shown as having one forked handle H, ornamented in relief, which has a grotesque head represented as biting the edge of the spout; but each spout may have a handle if the ewer is to be used as a vase. 45

I claim as my invention—

1. The design for a ewer herein shown and described, the same comprising the spherical body with spherical panels of a larger radius than the body proper placed diametrically opposite to each other, a base, and a neck 55 having semi-elliptical spouts, with a handle provided with a grotesque head, which is shown as biting the spout to which it is attached, substantially as described.

2. In a design for a ewer, the forked handle 60 having a grotesque head, which appears to grip or bite the edge of the spout, and otherwise ornamented in relief, substantially as described.

DAVID F. HAYNES.
